TABLE

Albert E. Sternkopf, Wauwatosa, Wis.

Application November 16, 1948, Serial No. 149,666

Term of patent 14 years

(Cl. D33—14)

To all whom it may concern:

Be it known that I, Albert E. Sternkopf, a citizen of the United States of America and a resident of Wauwatosa, in the county of Milwaukee and State of Wisconsin, have invented a new, original, and ornamental Design for Table, of which the following is a specification, reference being had to the accompanying drawing, forming a part thereof.

In the drawing:

Fig. 1 is a bottom perspective view of a table embodying the present invention, the table being shown as it appears when in raised position; and

Fig. 2 is a bottom perspective view of the table as it appears when in lowered position.

I claim:

The ornamental design for a table, as shown.

ALBERT E. STERNKOPF.
